(57) **CLAIM**

The ornamental design for a sound bar, as shown and described.

DESCRIPTION

FIG. 1 is a front perspective view of a sound bar showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is an enlarged view of the claimed portion of FIG. 1, shown separately for clarity of illustration.

The evenly dashed broken lines in the drawings illustrate portions of the sound bar that form no part of the claimed design. The dot-dash broken lines in the drawings define the boundary of the claimed design and form no part thereof.
